By James L. Norris

UNITED STATES PATENT OFFICE.

GIULIO RUSCONI-CLERICI, OF MILAN, ITALY.

CYCLE.

SPECIFICATION forming part of Letters Patent No. 674,196, dated May 14, 1901.

Application filed August 30, 1898. Serial No. 689,862. (No model.)

To all whom it may concern:

Be it known that I, GIULIO RUSCONI-CLERICI, engineer, a subject of the King of Italy, residing at Milan, Italy, have invented cer-
5 tain new and useful Improvements in Cycles, of which the following is a specification.

This invention relates to bicycles; and it includes certain novel features of construction hereinafter described and claimed.

10 The invention is shown in the accompanying drawings, in which—

Figure 1 is a side elevation of a bicycle involving my improvements, and Fig. 2 is a front elevation of the same.

15 Like characters refer to like parts in both figures of the drawings.

In the drawings I have represented a bicycle of the safety kind, it having a fork C², having a spindle or stem C', provided with a 20 head or enlargement C³, to which the brace-arm F' is rigidly secured and which extends oppositely from said head. A second arm is shown at F, it being loosely mounted at its middle on said spindle or stem C'.

25 The wheel shown is for two riders, and hence two handle-bars are provided, these being denoted by G and G' and having depending spindles G² and G³, respectively, rotatively carried at the opposite ends of the arms F and F'.

The spindle C' has fixed thereon a double-grooved pulley H'', and the handle-bar spindles G² and G³ are connected by bands J' and

J² with the double-grooved pulley H', it being evident that the pulleys H and H' are in the 35 same horizontal planes as the respective sections of the double-grooved pulley H''.

It will be understood that the bicycle is for two riders and necessarily has two saddles and duplex driving mechanism; but as these 40 features form no part of the present invention they are not, with the exception of one of the saddles E', shown in the drawings.

What I claim is—

The herein-described safety-bicycle having 45 two oppositely-arranged seats, driving mechanism for said bicycle, a steering-fork having its spindle or stem provided with a double-grooved pulley, one portion of which is arranged above the other, an arm loosely mount- 50 ed at its middle on said spindle or stem, a brace-arm rigidly connected to a head on the steering-fork, located below said arm, two handle-bars having depending stems rotatively carried at the opposite ends of both 55 arms, pulleys located respectively in the horizontal planes of the portions of said grooved pulley, and bands connecting said double-grooved pulley and said other pulleys.

In witness whereof I have hereunto set my 60 hand in presence of two witnesses.

GIULIO RUSCONI-CLERICI.
